TOOL

Filed Aug. 24, 1929

UNITED STATES PATENT OFFICE

WILLIAM J. DE WITT, OF AUBURN, NEW YORK, ASSIGNOR TO SHOE FORM CO., INC., OF AUBURN, NEW YORK, A CORPORATION OF NEW YORK

TOOL

Application filed August 24, 1929. Serial No. 388,105.

This invention relates to a tool for shoe forms by the use of which the insertion into and removal from a shoe of a form is facilitated, preferably for use with those forms adapted to be inserted in the toe of a shoe and having a transversely extending brace by which the walls of the form are expanded and contracted. In inserting a form of this type in a shoe it is the usual practice to contract the walls of the form by actuating the brace, insert the form firmly into the toe of the shoe and then actuate the brace a second time to expand the walls of the form and thus plump out into the desired position the material forming the toe of the shoe. When the form is removed from the shoe the side walls of the form are first contracted by actuating the brace and the form is then withdrawn with ease. The primary object of this invention is to provide a tool by which can be carried out any or all the various operations above mentioned such as inserting and removing the form and actuating the brace to expand or contract the walls thereof.

One embodiment of such tool is set forth in the specification and shown in the drawings which form a part thereof and in which,

Fig. 1 is a side elevation with parts broken away of a form inserted in the toe of a shoe by the use of the tool which embodies this invention;

Fig. 2 is a plan view illustrating the manner in which the tool is used with a form having one type of transversely extending brace for shifting the brace in one direction;

Fig. 3 is a view similar to Fig. 2 illustrating the way in which the forming tool engages the brace to shift it in the opposite direction and to remove the form from a shoe;

Fig. 4 is a plan view of such a tool;

Fig. 5 is a side elevation thereof;

Fig. 6 is an enlarged view of the operating end of the tool;

Fig. 7 is an enlarged sectional view taken along the line 7-7 of Fig. 6; and

Fig. 8 is a view similar to Fig. 3 illus-

trating the use of the tool with a form provided with a different type of brace.

Referring to Fig. 1, a form 10 is shown inserted within the toe 11 of a shoe by the use of an iron 12 which embodies one form of this invention. The tool 12 is preferably provided with a suitably curved shank 13 terminating at the forward end in a loop 14 and at the rearward end in a loop 15. The loop 15 is preferably larger than the loop 14 and under ordinary conditions is used as a handle. The end 16 of the tool forming the loop 14 terminates in an inclined tip 17 and is slightly offset from the other wall of the loop and spaced therefrom to form a passage 18. Across the end of the loop 14 is cut a transverse notch 19.

As clearly shown in Fig. 1 the tool 12 is inserted into the form 10 resting against the forward end thereof and by it the form 10 is pushed forward into the shoe until it reaches the final position. The form 10, particularly as shown in Figs. 2 and 3, is provided with a transversely extending brace 20 pivotally secured to one wall of the form and having a sliding engagement relative to the other.

If the sliding engagement of the brace 20 with the wall of the form be such that by swinging the brace forwardly the form will expand, the tool 12 is now placed against the brace (see Fig. 2) and by applying a forward pressure the brace will be shifted and the form expanded until the desired position has been reached. The notch 19 receives the brace and insures that the brace remain in engagement therewith. When a toe form of this type is to be removed from the shoe the tool is inserted beyond the brace and then retracted, the brace entering the loop 14 through the passage 18 by the assistance of the tapered tip 17. A pull on the tool 12, as shown in Fig. 3, will shift the brace rearwardly and if the pressure continues the form will be withdrawn from the shoe.

If, on the other hand, the cross brace 20 is of the type which necessitates a backward movement in order to expand the walls of the form, the tool 12 may be used, as shown

in Fig. 3, for this purpose, and as shown in Fig. 2, for the purpose of contracting the walls. With such type of brace the form must of course be removed manually by 5 grasping the upper end of the form.

One type of form that may be used is shown in Fig. 8 in which the walls of the form 30 are connected by a brace 31 which terminates at one end in a pointed tongue 10 projecting through a slot 32 into engagement with the inner sole of the shoe. In such case the end of the brace must be raised before actuating the brace to expand or contract the form. The tip 17 of the tool may 15 be slid over the flange of the form and below the end 33 thus raising the tongue from engagement with the inner sole. The brace 30 may then be actuated in the proper direction or the form may be withdrawn or 20 inserted by twisting the tool sufficiently to bind the brace.

The end of the tool having the loop 15 may be used when desired to insert a wide form into a shoe and the loop may be formed 25 in the same way as the loop 14. It has been found however that under ordinary conditions all the operations upon the braces may be performed by the smaller loop 14.

While one embodiment of this invention 30 has been shown and described I am not limited thereto since other embodiments may be made without departing from the spirit and scope of the invention as set forth in the following claim.

35 I claim:

A tool for inserting and withdrawing shoe forms of the kind which have laterally spaced walls and a pivotally mounted cross-brace for expanding and contracting the form, said tool comprising a shank provided at one end with a loop having a notch 40 in its foremost end for engaging the cross-brace when it is desired to swing the brace forwardly to expand the form within a shoe, said loop being open to receive the cross-brace when it is desired to swing the brace 45 rearwardly to contract the form.

Signed by me at Auburn, New York, this 50 21st day of August, 1929.

WILLIAM J. DE WITT.
